UNITED STATES PATENT OFFICE.

WILLIAM H. GAILOR, OF SARATOGA SPRINGS, NEW YORK.

ROAD-OILER.

1,038,340.

Specification of Letters Patent. Patented Sept. 10, 1912.

Application filed May 13, 1910. Serial No. 561,062.

To all whom it may concern:

Be it known that I, WILLIAM H. GAILOR, a citizen of the United States, residing at Saratoga Springs, in the county of Saratoga and State of New York, have invented an Improvement in Road-Oilers, of which the following is a specification.

My invention relates to improvements employed in connection with the road oiling devices shown and described in my application for Letters Patent of the United States filed July 24, 1909, Serial No. 509,458. In this and other devices employed by me as road oilers, a steam boiler and fire thereunder have been employed and the steam generated was utilized to heat the oil or other material employed to effect its delivery on the surface of the road. In this device much valuable heat and energy were lost and the apparatus could not be run with a maximum economy or the oil delivered upon the road carrying sufficient units of heat.

In my present invention the steam boiler with its fire and the use of steam therefrom for heating the oil or other material are dispensed with and a fire is employed under the tank holding oil or other suitable material, and this fire heats the oil or other suitable material employed, and the hot gases or products of combustion of said fire are utilized and directed through a heating chamber containing a reservoir, a distributer reservoir and connecting pipes for the oil or other material to be delivered upon the road so that these smaller bodies containing the material moving therein are additionally heated by the hot products of combustion coming from the combustion chamber and passing away by one or more stacks or chimneys rising from the heating chamber.

In the drawing, Figure 1 is an elevation and partial section representing the essential features of my improvement; the section being taken through the case of the heating chamber and also through the case of the distributer reservoir. Fig. 2 is an elevation and vertical longitudinal section at about the dotted line x, x , of Fig. 1, and Fig. 3 is an elevation and vertical longitudinal section similar to the section Fig. 2 but illustrating another form of my apparatus.

Similar letters of reference in the several figures indicate similar parts.

In these figures of the drawing, the oil tank or tank holding other suitable material to be heated and delivered upon the surface

of a road is represented at 10, and at 11 there is a long pipe reservoir and between the tank and the reservoir a pipe 12 and a controlling valve 13 therein. The distributer reservoir 60 is represented at 14 and connecting the same and the reservoir 11 there are series of pipes 15 with valves 16 therein.

The distributer reservoir 14 is preferably formed of plate metal with one side fixed 65 and one side adjustable so that there is a delivery slot 17 between said two parts which is regulated by one or more adjusting bolts 18. So far as just described, these parts agree substantially with similar parts 70 shown and described in my aforesaid application and which are employed for bringing the oil or other suitable material from a common tank 10 to the reservoir 11 and therefrom to the distributer reservoir 14 and 75 delivering the same upon the surface of the road, oiling the road or otherwise treating the same.

The special features of my present invention comprise a casing beneath and along 80 the tank 10 forming a fire-box or combustion chamber a , which may be constructed in any desired or suitable manner and at one end is preferably provided with a baffle-plate a' . The casing comprising sides 2, 4, 85 a bottom 3, a top 5 and ends 6 of plate metal is employed and surrounds and entirely encloses the reservoir 11, pipe 12, valve 13, distributer reservoir 14, series of pipes 15 and their valves 16, with the handles of the 90 valves 13 and 16, extending through the top 5 and side 4 of the casing for their proper operation. The casing of these parts comprises a heating chamber b connecting with the combustion chamber a and rising from 95 this heating chamber is one or more stacks c .

I have in the drawing shown two stacks, one at each side of the stem and handle of the valve 13 which permit of the operation of the valve when in the position illustrated. 100 I have shown within this heating chamber a swinging baffle-plate d upon a shaft d^1 , both of which preferably run the entire length of the heating chamber b ; there being a handle d^2 at one end upon the shaft d^1 outside the heating chamber for actuating the swinging baffle-plate. This baffle-plate comprises parts at an angle to one another with the shaft d^1 located at the intersection. 105

In Fig. 2 I have shown the baffle-plate d 110 in its two extreme positions. In the full line position one edge comes up against the

under side of the tank 10 and the other edge rests upon the reservoir 11. In the dotted position the one edge rests upon the upper surface of the baffle-plate a^1 and the other edge comes up against the under surface of the pipe 12.

The casing constituting the fire-box a may be of any desired construction for holding a fire of wood or coals for heating the tank 10 and the contents thereof; the portion shown in Fig. 2 being only the combustion chamber away from the fire portion.

All the hot gases and products of combustion must pass beneath the tank 10 and the upper edge of the baffle-plate a^1 , through the heating chamber b and away by the stack. In the full line position of the swinging baffle-plate d these products of combustion are by said baffle-plate diverted down into the lower portion of the heating chamber b where they entirely surround the reservoir 11, distributor reservoir 14, pipes 15 and valves 16 and must pass beneath the baffle-plate d before rising into the upper part of the heating chamber b around the pipe 12 and valve 13 before escaping by the stack or stacks c . Thus the devices through which the oil or other materials pass from the tank to be distributed upon the road are not only thoroughly heated, but brought to a high heat and the contents brought to a higher heat than would be possible by the use of steam as I have heretofore employed it. The full line position of this swinging baffle-plate is that employed in the operation of the device, while the dotted line position is that usually employed in starting the fire where one edge of the swinging baffle-plate rests upon top of the baffle-plate a^1 and the other edge comes beneath the pipe 12, giving ready access to the stacks or chimneys. In fact I prefer to put the handle d^2 upon the shaft d^1 of the swinging baffle-plate in such a position that it will assist in keeping the baffle-plate in the full line position Fig. 2, for use.

In the device of my invention, the hot oil or other material is evenly distributed upon the ground or surface of the road closely adjacent thereto. The bottom of the casing or heating chamber also comes close to the ground and serves to heat the surface of the earth somewhat before the oil or other hot material is delivered thereon, and in this manner both the heating of the material to be delivered and the heating of the surface to receive the material being delivered are facilitated.

Referring particularly to Fig. 3, which represents a second form of my apparatus, similar parts having similar letters and numerals of reference as in the other figures, except that in this figure the casing below and at the rear of the oil tank 10 is

so arranged and constructed as to provide an uptake chamber e , with an opening at the upper end thereof into the stack c controlled by a valve or damper 7 and also an uptake still at the rear of the uptake e designated by the reference letter f in which below the plane of the valve or damper 7 is placed a valve or damper 8, while a baffle-plate of fixed construction is indicated at d^3 , and in the operation of this structure the heated gases and products of combustion from the fire-box or combustion chamber a beneath the oil tank 10 pass over the baffle-plate a^1 , beneath the fixed baffle-plate d^3 circulating through the heating chamber b and around the various devices therein conveying oil or other suitable material from the tank 10 up the passage-way f , with the valve or damper 8 in the upright open position shown in Fig. 3 and away by the stack c . Thus the products of combustion and hot gases are utilized to thoroughly heat the various conveying devices in the heating chamber b .

In starting up the fire under the tank 10 it is preferable to close off the valve or damper 8, that is, by turning the same into a horizontal position and by opening the valve or damper 7; that is, by turning the same into a horizontal position, in which case the passage-way f being closed off the products of combustion pass up the passage-way e through the throat, past the damper or valve 7 and away by the stack c .

When the fire gets going and it is desired to heat up the devices in the heating chamber b , the damper or valve 7 is turned into a vertical position as shown in Fig. 3, to close off the connecting throat between the passage-way e and the stack; thus compelling all the products of combustion and hot gases to pass through the heating chamber b around the devices contained therein and up the passage-way f to the stack c .

I claim as my invention:—

1. In a road oiler, the combination with a tank for oil or other suitable surfacing material and devices for conveying such material from the tank and distributing it upon the surface of the road, of a casing forming a fire or combustion chamber beneath the tank, a casing connected therewith and surrounding all the conveying devices for the material, having open communication with the first casing or combustion chamber and forming a heating chamber, an outlet stack therefrom, a baffle plate at the union of the two casings over which the products of combustion pass from beneath the tank, a swinging baffle-plate within the heating casing comprising parts at an angle to one another adapted at one edge in one position to rest upon the top of the baffle plate and in the other position to lie in proximity with the under surface of the tank for changing the

direction of the movement of the escaping products of combustion, a shaft at the intersection of said parts at one end extending outside of the casing and means connected thereto and manually actuated for changing the position of the swinging baffle plate.

2. In a road oiler, the combination with a tank for oil or other suitable surfacing material and devices for conveying such material from the tank and distributing it upon the surface of the road, of a casing forming a fire or combustion chamber beneath the tank, a casing connected therewith and surrounding all the conveying devices for the material, having open communication with the first casing or combustion chamber, and forming a heating chamber, an outlet stack therefrom, a baffle-plate at the place of union of the two casings and over which all the hot gases and the products of combustion are compelled to pass from beneath the tank, and a swinging baffle-plate adapted at one edge in one position to rest upon the top of this baffle-plate and in the other position to lie in proximity with the under surface of the tank for changing the direction of the movement of the escaping products of combustion.

3. In a road oiler, the combination with a tank for containing oil or other suitable material for treating a road, a reservoir, a pipe and valve connecting the same with the tank, a distributor reservoir located below the aforesaid reservoir and a series of pipes and valves connecting the reservoirs, of a casing inclosing and surrounding the said reservoirs, pipes and valves and forming a heating chamber, one or more stacks rising from said casing, a casing beneath the tank forming a fire-box and combustion chamber and having communication with the said heating chamber, and a swinging baffle-plate, adapted in one position to direct the hot gases and products of combustion directly into the upper part of the heating chamber, and in the other position to divert the hot gases and products of combustion into the lower part of the heating chamber, to pass around the aforesaid devices therein.

4. In combination with a distributor, a receptacle, a fire-box for heating said receptacle, a flue for the fire-box, a conduit leading from the receptacle outside of said

fire-box, a casing independent of the fire-box and surrounding the conduit, and means for directing the hot gases from the fire-box to the flue over variable portions of the surface of said conduit.

5. In combination, a receptacle, a fire-box for heating the receptacle, a flue, a distributor nozzle, a conduit leading from the receptacle to the nozzle, a portion of said conduit passing through the flue, a casing independent of the fire-box and surrounding that part of the conduit which is outside the flue, and means for conducting the hot gases directly up said flue or about the whole of the conduit.

6. In combination, a receptacle, a fire-box for heating the receptacle, a flue, a header, a conduit leading from the receptacle to the header, a valve in the conduit, a distributor nozzle, connections between the header and the nozzle, a casing independent of the fire-box surrounding the conduit, the header and the nozzle connections and a damper for directing the hot gases from the fire-box directly to the flue or about the whole of the conduit, the header and the nozzle connections.

7. In a road oiler, the combination with a tank for oil or other suitable surfacing material, and devices for conveying such material from the tank and distributing it upon the surface of the road, of a casing forming a fire or combustion chamber beneath the tank, a casing connected therewith and surrounding all the conveying devices for the material, having open communication with the first casing or combustion chamber and forming a heating chamber, an outlet stack therefrom, a baffle-plate at the union of the two casings, over which the products of combustion pass from beneath the tank, and a second baffle-plate having one edge located above and coacting with the aforesaid baffle-plate in establishing a passage-way between the combustion chamber and heating chamber, said second baffle-plate extending into the heating chamber.

Signed by me this 2nd day of May 1910.
